UNITED STATES PATENT OFFICE.

ALBERT J. ROSENTRETER, OF BOONTON, NEW JERSEY, ASSIGNOR TO EDGAR ZABRISKIE, OF MAPLEWOOD, NEW JERSEY, AND FRANK E. HUTCHINS, OF NEW YORK, N. Y.

ELEVATOR-DOOR MECHANISM.

Application filed February 12, 1926. Serial No. 87,768.

This invention relates to improvements in elevator door mechanisms and has particular reference to non-reversing mechanisms for sliding doors.

5 In order to promote safety in the operation of elevators, it is necessary that each of the doors at the various landings be completely closed while the elevator is at some other landing. Serious accidents have been 10 caused by irresponsible people opening elevator doors from the outside while the elevator was not in position to receive passengers or the like through that particular door. Although a number of practical locking means 15 as such have been devised, there is a possibility of carelessness on the part of the elevator operator which sometimes leads to leaving the door in a partly closed position. With the present invention, the possibilities 20 of tampering with the door from the outside are reduced to a minimum, by requiring that the door be fully closed before it can be reopened.

An important object of the present invention is to provide an elevator door with a non-reversing mechanism which will practically eliminate the possibility of opening the door from the exterior of the elevator shaft.

30 Another object is to provide such a device which will require the door to be moved through its full limit of motion in closing it before it can be reopened.

Another object is to provide such a device 35 which will be simple in construction, strong and durable in service, economical to manufacture, and an improvement in the art.

Other objects and advantages will be apparent from the following description taken 40 in connection with the accompanying drawings, wherein a preferred embodiment of the invention is shown by way of illustration.

In the drawings, Figure 1 is a fragmentary 45 view of an elevator door equipped with the non-reversing mechanism of this invention, the door being shown in closed position;

Figure 2 is a view similar to Figure 1 and showing the door partly opened;

50 Figure 3 is an enlarged detail elevation of the non-reversing mechanism;

Figure 4 is a horizontal, sectional view on the line 4—4 of Figure 3;

Figure 5 is a view similar to Figure 3,

showing the relative positions of the parts 55 as the door is commencing to open;

Figure 6 is a view similar to Figure 5 after the parts of the non-reversing mechanism have become disengaged; and

Figure 7 is another view similar to Figure 60 5, showing the action of the non-reversing mechanism in holding the door against reversal at an intermediate position.

In the drawings, the reference character 10 designates a sliding elevator door of any 65 ordinary or preferred construction, and 11 is the usual paneled door or stationary wall. Secured to the inner surface of the door 10 is a mounting plate 12 which may be held by 70 screws 13 or other suitable fastening elements, and pivoted to the mounting plate by means of a bolt 14 is a door opening lever 15. The lever 15 is provided with a hand-grip 16 at one of its ends and has its other end pivoted as at 17 to a toggle link or the 75 like 18, to which, if desired, may be connected a check mechanism 19 such as disclosed in my United States Letters Patent 80 No. 1,487,027, issued March 18, 1924. The lever 15 and link 18 are preferably so proportioned and assembled as to be in horizontal alinement when the door is fully closed, as shown in Figure 1.

In order to prevent reversal of movement of the door within certain limits of its travel, a ratchet member 20 is pivotally mounted 85 upon the plate 12 for actuation by and with the lever 15, said ratchet member having a plurality of teeth 21 arcuately disposed upon one of its edges. Also, pivoted as at 22, upon 90 the plate 12 is a pawl 23 which is shown in the drawings as having a T-shaped body with a pointed nose 24 for engagement with the teeth 21 on the ratchet. The depending portion 25 of the pawl 23 serves as a balance 95 weight so that the pawl will normally maintain a position as shown in Figures 3 and 6, and it is free to move about its pivot 22 under the force of gravity.

When the door 10 is in its closed position 100 as shown in Figure 1, the pawl 23 and ratchet 20 are out of engagement. As the lever 15 is actuated by the elevator operator to open the door 10, it moves in a direction indicated by the arrow A in Figure 5, 105 whereupon the ratchet 20 comes in contact with the nose 24 of the pawl and moves it upwardly to a position shown in Figure 5

to permit passage of the ratchet by the pawl. The movement and the disposition of the ratchet and pawl are preferably such that when they are in mesh during the opening of the door, it cannot be closed until such a range of opening movement of the door is effectuated as to carry the ratchet out of mesh with the pawl. This is because of the fact that the ratchet and pawl bind and automatically lock the door if an attempt is made to close the door while the pawl is rocked in the manner shown in Fig. 5. When the opening movement of the door is continued so that the ratchet 20 moves beyond the influence of the pawl 23, as shown in Figure 6, the pawl swings about its pivot 22 to assume its normal position.

In closing the door the operation is similar but in a reverse direction, and, in view of the fact that the pawl 23 is free to move in either direction about its pivot 22, the nose 24 of the pawl will be moved downwardly by the ratchet 20, as shown in Figure 7. When the non-reversing mechanism is in this position, the door is almost entirely closed, and any attempt at reversing the movement to reopen the door will be stopped by the pawl 23 automatically locking with the teeth 21 of the ratchet. In order to reopen the door it is, therefore, necessary that the door be completely closed so that the lever 15 assumes its original horizontal position and the ratchet 20 passes entirely beyond engagement with the pawl 23.

If when the door 10 is in an open position a sudden and strong movement should be imparted to the operating lever 15, the pawl 23 would have a tendency to swing completely about its pivot and this would prevent proper engagement of the nose of the pawl with the teeth of the ratchet. Therefore, in order to prevent overthrow of the pawl, a stop pin 26 extends outwardly from the surface of the plate 12 and is so disposed as to prevent passage of the depending portion 25 of the pawl.

From the foregoing, it will be evident that a non-reversing mechanism for elevator doors has been provided which is of extreme simplicity and which will be thoroughly dependable in use. By its use improper opening of the elevator door, by irresponsible people, from the outside of the shaft will not be possible. The invention is of course susceptible of modification, and the right is herein reserved to make changes in the form, proportions, and arrangement of parts, being limited only by the scope of the appended claims.

Having thus described my invention, what I claim is:

1. In a mechanism of the character de-

scribed, the combination with a sliding door having means for moving the same to open or closed position, of means bodily movable with the door to prevent reversal of movement of the door in an intermediate position during its movement in either direction.

2. In a mechanism of the character described, the combination with a sliding door having means for moving the same to open or closed position, of pawl and ratchet mechanism movable with the door and cooperating to prevent its reverse movement from an intermediate position during its movement to either open or closed position.

3. In a mechanism of the character described, the combination with a sliding door, of a lever pivoted to the door and adapted to slide the same in either direction, a ratchet movable with the pivoted lever, and a pawl pivoted on the door to engage the ratchet, whereby to permit the continuous travel of the door in either direction and to prevent its reversal at intermediate points near the closing end of its travel.

4. In a mechanism of the character described, the combination with a sliding door, of a lever pivoted to the door and adapted to slide the same in either direction, a ratchet pivoted with the lever and movable therewith, and a pawl pivoted on the door to engage the ratchet during the movement of the door, said pawl and ratchet being out of engagement when the door is in either of its extreme positions whereby to swing the pawl to permit passage of the ratchet in either direction, and the pawl preventing reverse movement of the ratchet from an intermediate point at the closing end of the door's travel.

5. A non-reversing mechanism for elevator doors, comprising a ratchet, and a gravity actuated pawl pivoted to swing in either direction whereby to alternately act upon the pawl in opposite directions, said pawl and ratchet being mounted for relative movement as an elevator door is moved, and being out of engagement with each other when the door is in either of its extreme positions.

6. A non-reversing mechanism for sliding doors, comprising door operating means, and, in combination therewith, means for automatically locking such operating means against movement in a direction reverse to a movement of the operating means in a given direction, such locking means comprising interengaging members respectively on the door and the door operating means, and acting only intermediately of the ends of the movements of the operating means.

ALBERT J. ROSENTRETER.
